UNITED STATES PATENT OFFICE.

ANDERSON CARTER, OF STALLO, MISSISSIPPI.

CLEVIS.

Application filed January 26, 1923. Serial No. 615,175.

To all whom it may concern:

Be it known that I, ANDERSON CARTER, a citizen of the United States, residing at Stallo, in the county of Neshoba and State 5 of Mississippi, have invented new and useful Improvements in Clevises, of which the following is a specification.

An object of this invention is to produce a clevis for plows, cultivators and the like 10 in which the draft end or draft bar thereof is pivotally mounted thereon and normally held in closed or operative position by spring locking means, and in which means is provided for releasing the locking means 15 when it is desired to detach the draft animals.

To the attainment of the foregoing and other objects which will present themselves as the nature of the invention is better understood, reference is to be had to the drawing which accompanies and which forms 20 part of this application.

In the drawing:—

Figure 1 is a side elevation of a clevis in 25 accordance with this invention, the dotted lines showing the pivoted end or gate in open position.

Figure 2 is a top plan view thereof.

Figure 3 is a sectional view on the line 30 3—3 of Figure 2.

Figure 4 is a section on 4—4 of Figure 1.

In the drawing, the numeral 1 designates the forward part of a plow beam, and 2 designates the vertical bar of the clevis having the parallel extending arms 3 and 4 which are disposed over the upper and lower faces of the beam 1 and which are secured thereon by the usual wrench bolt 35 5.

The vertical bar 2 is in contact with the outer end of the beam 1, and the lower bar or arm 3 of the clevis projects a considerable distance beyond the upper bar 4 thereof. To the end and to the upper face of 40 45 the arm 3 there is hinged, as at 6 the movable element or draft bar 7 of the clevis. The member 7 is of the usual construction, the same having its upper end provided with an arm 8 that is directed toward the

arm 4 of the fixed element of the clevis. The arm 8 has its end provided with a reduced rounded extension 9 that is designed to be received in a socket 10 in the outer end of the arm 4 when the swinging member 50 or draft bar 12 of the clevis is in normal position.

Secured to the outer surface of the arm 8 of the swinging member of the clevis there is one end of a flat spring 11, the said spring being rounded adjacent its outer end 60 to provide a hooked portion 12 designed to be brought over a lip 13 integrally formed on the outer surface of the arm 4. From the hook the sprng is rounded to provide the same with a curved lip 14, and this lip 65 is designed to be engaged by a ring member 15 which is hinged, as at 16 to the outer face of the arm 4 of the clevis. If desired, there may be attached to this ring 16 a flexible element such as a cord or chain 17, and a pull thereon will swing the angularly disposed ring out of engagement with the lip 14 of the spring, permitting of the latter 70 springing outwardly to bring its hook 12 out of engagement with the lip 13 and consequently permit of the free swinging in 75 an outward direction of the section 7 of the clevis on the fixed section thereof.

It is thought that the foregoing description, when taken in connection with the 80 drawing will fully set forth the construction, operation and advantages of the improvement to those skilled in the art to which this invention relates, it being merely necessary to swing the section 7 to 85 bring the end 9 thereof into the socket 4 of the upper arm of the fixed section of the clevis and thereafter to exert a pressure against the spring to bring the hook portion 12 thereof to engage with the lip 13, 90 when the ring can be swung over the lip 14 of the spring. With my improvement, fractious animals may be readily released without danger to the implement to which they are hitched or danger to the driver 95 thereof. The improvement, as above inferred, also materially facilitates the arrangement of the eye of the single tree thereon as well as its removal therefrom.

Having described the invention, I 100 claim:—

A clevis including a fixed section and a movable section which is hingedly secured to the fixed section, each of said sections having arms, the lower arm of the fixed section being of a greater length than the upper arm thereof, and the swinging section being hingedly secured to said lower arm, the swinging section having an arm directed toward the upper arm of the fixed section, said arm having a reduced end, the arm of the fixed section having a socket to 105 110

receive said end thereof, a flat arched spring secured to the said arm of the swinging section having a hook portion terminating in a lip, a lip formed on the upper arm of the fixed section to be engaged by the hook of the spring, and a ring pivotally secured upon the upper arm of the fixed section and

swingable to engage the lipped end of the spring for holding the hook portion thereof in engagement with the lip of said arm. 10

In testimony whereof I affix my signature.

ANDERSON CARTER.
